UNITED STATES PATENT OFFICE.

GEORGE F. VOIGHT, OF SAN FRANCISCO, CALIFORNIA.

DOOR-HANGER.

1,157,467.

Specification of Letters Patent. Patented Oct. 19, 1915.

Application filed September 30, 1914. Serial No. 864,257.

To all whom it may concern:

Be it known that I, GEORGE F. VOIGHT, a citizen of the United States, residing at San Francisco, in the county of San Francisco and State of California, have invented new and useful Improvements in Door-Hangers, of which the following is a specification.

The present invention relates to improvements in door hangers suspended from a wheel or wheels on an over-head track, and having lower portions adapted to be fastened to the upper portion of the door, one hanger at each of the upper corners of the door.

The object of the invention is to provide a hanger which can be installed with but little labor; which permits of a wide range of adjustment; which has few parts or joints liable to rattle; and which leaves the tops of the doors free from all metal projections, such as screw heads, metal plates and the like, that might interfere with its proper movement.

In the accompanying drawing, Figure 1 is a side elevation, certain parts being shown in vertical section, of an upper right-hand corner of a door, showing also the hanger attached thereto and a portion of a track from which said hanger is suspended; Fig. 2 is an edge view of the door showing the track and other parts in vertical section; Fig. 3 is a longitudinal central sectional view of the lower portion of the hanger proper; Fig. 4 is a perspective view of an upper right-hand corner of a door adapted to be connected to my improved hanger; Figs. 5 and 6 are side views of modified forms of the hanger detached from the door.

Referring to the drawing, 1 indicates a track, preferably made of wood nailed or screwed directly against the framework of the building above the door. Upon said track is mounted a wheel 2, centrally supporting a shaft 3 formed integral with, and from which depends, an upper hanger member 4 having a lower transverse or horizontally extending portion 5, through which extends a round hole or bearing 6, in the plane of the wheel 2. In said hole 6 is rotatably supported a round stem 7, extending from a lower hanger member 8, having a shoulder 9 abutting against an end of the transverse portion 5, said stem 7 being secured in said hole 6 by a cotter pin 10 passed through a transverse hole 11 therein. Said lower mem-

ber is goose-necked in form and has a narrow portion 12 extending through the narrow slot 13 between the head jambs 14. Below said narrow portion 12 the lower member 8 is of a general cylindrical form and extends in a direction making an angle of about 45° with the vertical, and is inserted in a cylindrical hole 15 in the corner of the door, also making the same angle therewith. The upper end of the hole in the door is formed at its shorter side with a narrow vertical extension 16, to accommodate the narrow portion of the hanger 12, in case it is rendered necessary by adjustment of the hanger in the door. The lower hanger member is secured in place in the door by means of a screw 17 passing through a hole in a plate 18 bent to form two mediate parts 19, 21, at right angles to each other and two terminal parts 22, 23, making with the adjacent mediate parts angles of 135°. The plate is secured to the door by means of a screw 24 passing through a hole in the lower terminal part 23 and screwed into the door, while the lower mediate part 21, of a general cylindrical form, rests against the side of the hole. The screw passes through a hole in the upper mediate part 19 and its head 20 abuts against said upper mediate part. Said screw 17 is screwed through a threaded hole in the lower end of the lower hanger member. The central portion of the part of said lower hanger member in the hole 15 is preferably flattened, and reduced in thickness, as shown at 25, to save material, and said flattened portion is centrally slotted longitudinally, as shown at 26, to facilitate the working of the screw.

It is preferable that the lower hanger member should be capable or a slight rotary motion relative to the upper member, but in the form of the invention shown in Fig. 5 the hanger is made all in one piece 27, its upper portion extending obliquely instead of vertically.

The form of the invention shown in Fig. 6 differs from that in Fig. 1 in that two wheels instead of one are employed for each hanger.

I claim:

1. The combination with a door having a hole extending obliquely through an upper corner thereof from one side edge to its upper edge, a hanger having a lower portion fitting slidably in said hole and having an upper portion overhanging said lower por-

tion, a plate resting against the side edge of the door and having a portion fitting in the lower end of said hole, and a screw extending through said portion of the plate and having a head housed therein, the shank of the screw threadedly engaging the lower end of the hanger.

2. The combination with a door having a hole extending obliquely through an upper corner thereof, the upper end of the hole being formed in its shorter side with a narrow vertical extension, a hanger having a lower portion fitting slidably in said hole and having an upper portion overhanging said lower portion, the hanger having a narrow portion between said upper and lower portions and adapted to be received by said exten-

sion of the hole, a plate resting against the door and having a portion fitting in the lower end of said bore, and a screw extending through said portion of the plate and having a head housed therein, the shank of the screw threadedly engaging the lower end of the hanger, and the lower portion of the hanger having a slot for receiving the shank of the screw.

In testimony whereof I have hereunto set my hand in the presence of two subscribing witnesses.

GEORGE F. VOIGHT.

Witnesses:
